FIG. 1.

FIG. 5.

FIG. 6.

FIG. 2.

FIG. 3.

FIG. 4.

FIG. 1 is a perspective view of the front and one side of a dispenser for liquids or fluidized powders showing my new design;

FIG. 2 is a front elevational view thereof;

FIG. 3 is an elevational view thereof of the side not visible in FIG. 1;

FIG. 4 is a rear elevational view thereof;

FIG. 5 is a top plan view thereof; and
